(57) **CLAIM**

The ornamental design for a motor, as shown and described.

DESCRIPTION

FIG. 1 is a top, front, right side perspective view of a first embodiment of a motor, showing our new design;
FIG. 2 is a bottom, rear, left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan thereof;
FIG. 9 is a cross-sectional front elevation view the motor of FIG. 1, taken in a direction of line 9-9 in of FIG. 6;
FIG. 10 is a top, front, right side perspective view of a second embodiment of a motor, showing our new design;
FIG. 11 is a bottom, rear, left side perspective view thereof;
FIG. 12 is a front elevation view thereof;
FIG. 13 is a rear elevation view thereof;
FIG. 14 is a left side elevation view thereof;
FIG. 15 is a right side elevation view thereof;
FIG. 16 is a top plan view thereof;
FIG. 17 is a bottom plan thereof; and,
FIG. 18 is a cross-sectional front elevation view of the motor of FIG. 10, taken in a direction of line 18-18 of FIG. 15. The equal-length broken lines in the drawings depict portions of the motor that form no part of the claimed design.

1 Claim, 18 Drawing Sheets
